RADIATOR CAP

Filed Jan. 10, 1922

UNITED STATES PATENT OFFICE.

ISAAC LEO WOLKOW, OF LOUISVILLE, KENTUCKY, ASSIGNOR TO THE KINGSLEY-MILLER COMPANY, OF CHICAGO, ILLINOIS, A CORPORATION OF ILLINOIS.

RADIATOR CAP.

Application filed January 10, 1922. Serial No. 523,202.

My invention relates to new and useful improvements in automobile radiator caps and has for its principal object the construction of the cap in such a manner that it may be easily 5 screwed onto the thimble or sleeve surrounding the filling opening of the radiator but cannot be unscrewed without detaching the radiator and reversing the same, thereby preventing the loss of the cap by theft.

Another object resides in forming the cap so that it may have a temperature indicator or "motormeter" secured thereto, means being provided to prevent the removal of the indicator after it has been secured in place.

A further object consists in forming the cap with a hinged section or cover adapted to be swung to allow for the filling of the radiator and providing means for securing the hinged section against swinging movement 20 when it is not necessary to fill the radiator.

A still further object resides in the provision of means whereby the cap may be removed, if desired, when the radiator has been removed from the automobile, such removal 25 of the cap being allowed only when the position of the radiator is reversed or in other words when the radiator is turned upside-down.

With the above and other objects in view, which will appear as the description proceeds, my invention consists in the novel details of construction and arrangement of parts described in the following specification and illustrated in the accompanying drawings, and 35 while I have illustrated and described the preferred embodiments of the invention it will be understood that such changes may be made as will fall within the scope of the appended claims.

In the drawings:—

Fig. 1 is a front elevation.

Fig. 2 is a fragmental transverse vertical section.

Fig. 3 is a top plan of the base portion.

Fig. 4 is a bottom plan of the hinged portion or cover.

Fig. 5 is a side elevation of the locking rings in separated position.

Fig. 6 is a side elevation of the locking rings in interlocking position for screwing onto the radiator sleeve.

Fig. 7 is a bottom plan of the upper locking ring.

Fig. 8 is a top plan of the lower locking ring.

55

Fig. 9 is a transverse vertical section through the base with portions reversed for removal of the cap, and

Fig. 10 is a vertical detail.

In the drawings 1 indicates a preferably 60 exteriorly threaded sleeve, surrounding the filling opening of the radiator, to which my improved form of cap is adapted to be secured. The cap comprises a base 2 to which a cover 3 is hingedly connected by the pin 65 4, the cover having a recess 5 extending from the lower end to receive the stem 6 of a temperature indicator or "motormeter" 7 of any of the well known constructions. The stem 6 is exteriorly threaded and receives the 70 washer 8, the securing nut 9, and the lock nut 10, the washer and nuts being received in the recess 5 as quite clearly shown in Fig. 2 of the drawings. To prevent access to the securing

means for the temperature indicator I secure a plate 11 to the lower end of the cover by means of the screws 12, the plate having a 75 central opening through which the end of the stem passes. The edge of the opening in the plate is formed with the circumferentially 80 spaced inwardly extending projections 13

which extend into close proximity to the stem thereby preventing the insertion of tools or the fingers for removing the securing means on the stem. At the same time the projections being spaced apart allow for circulation 85 of the heat or other elements so as to not interfere with the ready operation of the indicator. In the form of cover illustrated in Fig. 1 laterally extending arms or wings 14

90 are provided and may be used for turning the entire cap for connecting the same to the radiator sleeve in a manner to be later described. In Fig. 10, of the drawings, I have illustrated the manner of securing the plate 11 to the cover, the cover being shown in 95 reversed position to more readily adapt the securing of the plate in position. The securing screws 12 will preferably be provided with the spaced heads 15, the outer head having a

100 slot for the insertion of a screw driver or similar tool. When the screw is inserted to its greatest extent the upper head 15 will break off at the reduced portion 16 and the lower head will be received in the recess 17

105 in the lower face of the plate. When the up-

per head is broken off it will be impossible to remove the screws as the lower head which is received in the recess 17 has no slot or similar openings for the insertion of removing tools.

The base 2 is provided interiorly with the shoulders 18 and 19, the shoulder 18 forming a seat for rotatably supporting the ring 20 and the shoulder 19 forming a seat for the ring 21 which is secured to the base by means of the screws 22 more particularly shown in Fig. 3 of the drawings. After the screws 22 have been driven home the outer ends will be filed off so that it will be impossible to remove said screws and the ring 21. The ring 20 is provided with the upwardly extending ratchet teeth 23 and the downwardly extending interiorly threaded sleeve or flange 24 the interior threads of said sleeve or flange being adapted to engage the threaded sleeve or thimble which surrounds the radiator filling opening. The ring 21 is provided on its under face with the ratchet teeth 25 which, when the two rings are in position, overlie and are adapted to engage the teeth 23 on the ring 20. The ring 21 is also provided with an inclined recess 27 forming the tooth 28 for a purpose to be later described. The ring 20 is provided with a recess 29 to receive, when the cap is attached in its operative position, a pin 30, said pin 30 adapted to fall into the recess 27, and engage the tooth 28, of the ring 21, when the radiator is removed from the automobile and its position reversed. This pin 30 will be used for removing the cap from the radiator, when desired, in a manner to be later described.

For securing the free edge of the cover to the base, I provide the screw 31 which is adapted to engage in a threaded socket formed in the upper face of the base. By rotating said screw by the knob 32 the cover may be swung upon its pivot 4 to allow for filling of the radiator. When the screw is raised it will be received in the recess 33 formed in the under face of the cover.

As is quite clearly shown in Figs. 2 and 9 the ring 20 has a little play between the shoulder 18 and the ring 20. A packing ring 34 will be received on the ring 20 to form a tight fit, and to prevent rattling between the base and cover.

Having fully described the detail construction I will now endeavor to bring out fully the advantages and mode of operation. It is a well known fact that each year a large number of automobile radiator caps and temperature indicators or "motormeters" are stolen due to the fact that ordinarily the caps either with or without the temperature indicator are merely screwed upon the sleeve or thimble surrounding the filling opening of the radiator and they can be easily unscrewed and taken away. As has been stated in the objects of my invention I intend to provide

a radiator cap which may be easily attached to the filling opening but cannot be detached without reversing the position of the radiator or in other words turn the radiator upside-down. At the same time the temperature indicator or "motormeter" is so attached to the cap as to prevent its removal after it has once been secured in position. The ring 21 is secured to the base 2 by the screws 22 and therefore becomes a part of the base and is adapted to operate therewith at all times. The ring 20 whose extension 24 is interiorly threaded is adapted for rotatable movement with respect to the base and will only turn with the base when turning or screwing on to the filling opening thimble. In screwing the cap into position the teeth 25 of the ring 21 will engage the teeth 23 of the ring 20 and thereby rotate the ring 20 as a part of the cap and screw the same on to the radiator sleeve. Should an attempt be made to unscrew the cap the base 2 with the ring 21 will rotate free from the ring 20, the teeth 25 of the ring 21 being allowed to ride over the teeth 23 of the ring 20 due to the play left between the ring 21 and shoulder 18 of the base for the ring 20. It will therefore be seen that although the base 2 may be rotated in a direction supposedly to unscrew the cap from the radiator never-the-less the ring 20 with the threaded extension will not be unscrewed and therefore the cap cannot be removed from the radiator. The only way in which the cap may be removed is, as previously described, by taking the radiator off of the automobile and turning the same upside down. The pin 30 is normally entirely received within the opening or recess 29 of the ring 20 but when the radiator is turned upside down a portion of the said pin 30 will drop into the recess 27 of the ring 21 and engage the shoulder 28. The shoulder 28 being in reverse position to the teeth 25 will, when the pin 30 engages the shoulder 28 allow the ring 20 to be turned with the base and the ring 21 carried thereby, thereby unscrewing said ring and its threaded extension 24 from the radiator sleeve and allowing the cap to be removed. In order that the radiator may be readily filled, when necessary, I provide the hinged cover pivotally connected to the base and secured in close position by the screw 31. When it is desired to fill the radiator the knob 32 is turned so that the screw 31 will be withdrawn from the threaded opening in the base into the recess 33 and the cover can then be swung upon its pivot point 4 and the radiator filled. In order to prevent the stealing of the temperature indicator or "motormeter" I have provided the plate 11, having the inwardly extending projections 13, which is secured over the end of the recess 5, in the cover, and prevents any one from inserting their fingers or tools for removing the nuts 9 and 10 which secure said temperature indicator to the cap.

At the same time the inwardly extending projections 13 being circumferentially spaced there is nothing to prevent the ready circulation of heat to the temperature indicator stem 5 and therefore the operation is not impaired in any manner. The cap as a whole may be screwed into position by using the laterally extending wings or projections 14 as a handle or lever, although it will be understood 10 that said projections or wings form no particular part of the present invention and any other suitable design of cover may be equally as well used. As previously stated after the screws 22, which secure the ring 21 to the base 15 2, have been driven home the ends are filed off so that they cannot be removed. The screws 12, which secure the plate 11, to the cover, are preferably of the construction shown and described whereby when they are 20 driven home the upper head, containing the slot, will be broken off so that the screws cannot be removed.

Having fully described my invention what I claim as new and desire to secure by Letters 25 Patent is:

1. In combination with a radiator having a threaded sleeve around the filling opening,

a radiator cap, said cap comprising a base, a threaded ring rotatably carried by the base and adapted to engage the sleeve, said ring 30 having teeth thereon, a toothed ring rigidly connected to the base and adapted to engage the teeth of the rotatable ring for screwing said ring onto the sleeve but preventing rotation in the opposite direction, a pin normally carried within the rotatable ring but adapted upon reversal of the position of the radiator to engage the teeth of the rigidly connected ring to allow unscrewing of the cap from the sleeve, and a cover connected to the 40 base.

2. In combination, a closure for a radiator filling opening, means including two collars one fitting around the other for connecting said closure to said radiator but permitting 45 a limited opening movement thereof, said means being releasable from said radiator only when said radiator is in abnormal position, a slidible pin being associated with said means.

In testimony whereof I hereunto affix my signature.

ISAAC LEO WOLKOW.
